LAMP AND VARIABLE FOCUS SHADE

Nathan George Horwitt, Morris Katcher, and
Willi Noell, New York, N. Y., assignors to De-
sign Engineers, Incorporated, New York, N. Y.

Application August 13, 1934, Serial No. 739,546

11 Claims. (Cl. 240—108)

This invention relates to a lamp and shade for it. The shade is of flexible material, and so constructed that its shape can be changed to make its focus variable. An expanding and contracting mounting is provided for the shade to allow for its change of shape. The variable focus is of advantage where the lamp is used in either direct or indirect lighting. By lengthening the focus of the shade, the intensity of the lighting is decreased, while its spread is increased, and vice versa. This is especially advantageous in a floor lamp which can be adjusted in height as well. In a ceiling lamp, it will be valuable for controlling the height to which a wall may be illuminated. The latter advantage is ideal for picture galleries.

The lamp consists of a container within which an electric light bulb can be mounted. The container is open at one end, and opposite this end and in axial alignment therewith, is mounted the variable focus reflector or shade. By providing suitable supports, the lamp can be used as a floor lamp, desk lamp or ceiling lamp.

Other objects and advantages will become apparent upon further study of the description and drawings, in which:—

Fig. 1 is a vertical section of the lamp, the shade and certain other parts however being shown in elevation. The dot and dash lines show the shade changed in shape from providing a focus located a short distance down below it, to provide in one case a focus of infinite distance below the shade, and in the other case a virtual focus above the shade, the latter case dispersing the light outwardly from the shade.

Fig. 2 is a fragmental plan and horizontal section to an enlarged scale taken along the line 2—2 of Fig. 3.

Fig. 3 is a partial section to an enlarged scale through the upper end of the shade and its support, the ball and a portion of the stem of the supporting member being shown in elevation.

Fig. 4 is a sectional plan taken along the line 4—4 of Fig. 1.

Fig. 5 is a partial section to an enlarged scale taken similarly to Fig. 3, showing a modified support for the shade.

Fig. 6 is an elevation of the modified support, a portion of the shade being shown with a part broken away.

Fig. 7 is a top plan of the lower member of the modified support, said member being shown by itself.

Fig. 8 is a top plan of the shade by itself, the solid lines showing it in its most extended posi-

tion, that is when it is flat, while the dot and dash lines show it deformed into conical shape such as is seen in elevation in Fig. 1.

Fig. 9 is a partial section of the shade taken along the line 9—9 of Fig. 8, with the thumb wheel, gear and shaft shown in elevation.

Fig. 10 is a partial section taken along the line 10—10 of Fig. 9.

Fig. 11 is a broken apart perspective view of a portion of the shade at its mechanism for producing and maintaining the overlap of the edges of the shade at the split, with the housing over the driving gear omitted, and

Fig. 12 is an elevation of the lamp embodied in a floor lamp.

The shade 13 is formed of a flexible sheet of material. This material should be flexible with sufficient stiffness and resiliency to offer substantial resistance to change in shape. The term "flexible" as used in the claims is intended to be of such type. Parchment paper is suitable, as is thin sheet metal such as steel or brass. Thin sheets of phenol condensation products are also suitable.

Shade 13 is formed with an opening 14 in its central portion and a split extending from said opening to the outer edge of the shade. In its flat position, the shade is essentially a split ring with the outer edge of the shade preferably circular in plan. In our preferred form, the edges of the shade at the split just touch when the shade is flat, and in this position, which is the normal position, there are no internal elastic stresses in the shade. The numeral 15 denotes the left hand edge of the shade (Figs. 8, 10 and 11) at the split, while the numeral 16 denotes the right hand edge. In Fig. 8, where the solid lines represent the shade in flat position, right hand edge 16 cannot be seen, as it is immediately adjacent left hand edge 15, but below strip 17, as seen in Fig. 10. Strip 17 is provided, so that with the shade in flat position, there is no crack or opening up of the sheet at the split through which light can shine. Strip 17 also ensures that the left hand edge 15 will always ride over the top of the shade when edges 15 and 16 are made to overlap, which as will be explained later causes the shade to assume a conical shape.

Referring to Figs. 9, 10 and 11, the mechanism for effecting the overlap of the edges at the split and for retaining them in different amounts of overlap will be seen in detail. Strip 17 is provided with a bent back extension 18. Bearings 19 are punched up from extension 18 for supporting shaft 20 upon which is fixed driving gear 23.

Extension 18 is provided with a bent under tongue 21, having an opening 22 therein. In Fig. 11, tongue 21 is shown in dot and dash lines in extended position before being bent under.

- 5 Fixed upon the outer end of shaft 20 is thumb wheel 24. A washer 25 is provided on shaft 20 to prevent its axial motion outwardly. Enclosing driving gear 23, shaft 20 and bearings 19 is a housing 26, which is butt welded to the top of 10 extension 18.

As noted before, when the shade is flat, split edge 16 is adjacent split edge 15 but below it, strip 17 coming between said edges. The portion of the shade adjoining edge 16 is provided with 15 holes 27 in line with the teeth of driving gear 23 and adapted for engagement therewith. Opening 22 in tongue 21 is provided to allow clearance for the teeth of gear 23. The portion of the shade adjoining edge 16 extends under strip 17 20 but over tongue 21. Strip 17 is riveted to the portion of the shade adjacent edge 15, coming below said latter portion, with extension 18 coming over said latter portion. Extension 18 does not lie for its entire width in a plane parallel to 25 strip 17, its left hand portion, Figs. 10 and 11, being above the plane of top of strip 17, while its right hand portion is below and in contact with the portion of the shade adjoining edge 16.

30 A U shaped guide 28 is riveted to the shade at its outer edge, near split edge 16. The lower leg of the guide is fastened beneath the shade, (not seen) after edge 16 has been moved at least the width of the guide to the left of tongue 21, Fig. 11, the upper leg of the guide coming above 35 extension 18, Fig. 8. Another guide 29 is provided at the inner edge of the shade at opening 14. As seen more clearly in Fig. 9, the upper leg of guide 29 is riveted to the top of strip 17, with its lower leg coming below the shade at the portion 40 adjoining split edge 16.

Guide 28 also serves as a stop to prevent separation of edges 15 and 16 so that the shade is not opened up at the split. This would occur, referring to Fig. 10, when split edge 16 is moved 45 far enough to the right to be entirely clear of the right hand edge of strip 17. Guide 28 prevents this by butting against housing 26 when moved too far to the right.

50 When thumb wheel 24 is operated to rotate gear 23 clockwise, as seen in Fig. 10, edge 16 moves to the left and edge 15 to the right, causing the edges of the shade at the split to overlap. The sheet of material comprising the shade is distorted into substantially a cone by causing the 55 edges 15 and 16 to overlap, the flatness or sharpness of the cone depending on the amount of overlap. When the overlap is made greater the cone is sharper or has a smaller angle at the apex and vice versa. The friction between the 60 sliding parts, especially extension 18, and the resistance to turning of gear 23 and thumb wheel 24 provide a locking action for holding split edges 15 and 16 in the different amounts of overlap set.

65 In simplified form, the shade can be made without the mechanism for effecting the overlap, said overlap being effected by grasping with the fingers, the portions of the shade adjoining the split edges 15 and 16 and pushing them apart or together, the friction of the sliding parts holding the various amounts of overlap set, especially when tongue 21 is not bent down very far, so that it must be sprung to allow the portion of the shade adjoining edge 16 to pass between it and the bottom of extension 18 to the left, Figs. 10 70 and 11.

When the portions of the shade adjoining edges 15 and 16 are caused to overlap, the shade may assume a conical shape with the apex of the cone above its base, as shown in solid lines for the shade 13 in Fig. 1, or it may assume a conical 5 shape with the apex of the cone below its base as shown in dot and dash lines at A in said figure. When the sheet forming shade 13 has no internal elastic stress, with the shade in the flat position shown by the dot and dash lines of Fig. 1, marked 10 B, it must be intentionally flexed up or down, as overlap is given to the split edges to determine whether the base of the cone is above or below its apex. In another form, the sheet is formed with internal elastic stress in it tending normally and 15 automatically to cause the base to move down in a lamp of the type of Fig. 1 as said edges are caused to overlap. With other types of lamp, such as a ceiling lamp, this bias should be for the base to be above the apex. The advantage of the 20 bias is that when the shade is changed from flat position, it will automatically assume the conical shape most suitable for use with its particular type of lamp.

25 In Fig. 8, the solid lines show a plan view of the shade in flat position, corresponding to the flat position B shown in elevation by dot and dash lines in Fig. 1. The dot and dash lines in Fig. 8 show the shade in plan when split edges 15 and 16 have been given a substantial amount of overlap, and the shade has taken on a conical shape. It will be observed that inner opening 14 in the central portion of the shade becomes smaller as the overlap increases and vice versa. As the shade is mounted at its inner edge, that is at said 30 opening, a mechanism must be provided for supporting the shade, that expands and contracts with said inner edge.

35 A tubular casing 30 is provided with a base 31 in the desk type of lamp shown in Fig. 1. Upon base 31 is mounted lamp socket 32, shown holding a light bulb 33. The upper end of casing 30, which remains open, has three tubular sockets 34 arranged symmetrically within it at the third 40 points of its circumference. Fitting in sockets 34, are the prongs 35 which are twisted about each other at their upper ends to form a post 36. A tubular supporting member 37 has a forced fit over post 36. The upper end of member 37 is enlarged to form ball 38. In the type of expanding and contracting mechanism for supporting the shade, illustrated in Figs. 2 and 3, a piece 39, having an annular groove 40 is mounted on ball 38 and held thereon by nut 41. Pivot pins 42 are mounted in piece 39 and extend across groove 45 40 at its third points. Upon each pivot pin 42 is rotatably mounted a finger 43, the pin for each finger being near one end of the finger. Located between substantially the middle of each finger 43 and the inner face of groove 40 is a spring 44, 50 normally tending to force the free end of the finger out of groove 40. The outer face of each finger 43 is concave, preferably V shaped. The inner edge of shade 13 engages each finger at its 55 V shaped surface at about the apex of the V. When the area of opening 14 is decreased by increasing the overlap of edges 15 and 16 and thereby the sharpness of the cone angle of the shade, the inner edge of the shade presses back 60 fingers 43 into groove 40 against the pressure of springs 44. In other words, the surface supporting the shade contracts with the contraction of opening 14. When said opening expands, springs 44 cause the supporting surface to expand with it. 65 Piece 39 has a central opening 45 in which is 70 75

mounted a spring 46 pressing down a plunger 47 against the top of ball 38. This provides the necessary friction to hold piece 39 and with it shade 13 in the various positions in which they may be set.

A modified type of expanding and contracting mechanism for supporting the shade is shown in Figs. 5, 6 and 7, which consists essentially of discs 48 and 49 having their vertical axes in alignment and adapted for relative motion with respect to each other. In the embodiment shown, disc 49 is fixed against motion, while disc 48 is free to move. Disc 49 is held on ball 38 by nut 50. Extending from the top of ball 38 and fixed thereto is a post 51. Disc 48 is loosely mounted on post 51, a loosely mounted sleeve 52 fitting between the central hole of said disc and said post. The upper part of disc 48 is provided with an opening 53 to accommodate washer 54 which fits over post 51 and is normally pressed toward disc 48 by spring 55 which reacts at its upper end against collar 56 formed on post 51. Disc 49 which has the shape of a frustum of a cone, is provided with radial grooves 57. Disc 48 is provided with tongues 58 corresponding to grooves 57 and entering same. Tongues 58 have a surface inclining back from the outer edge of disc 48 toward its center. The inner edge of shade 13 is gripped by the discs along a line determined by the intersection of the inclined surface of the tongues 58 and the conical surface of disc 49, see especially Fig. 6. As the area of opening 14 of the shade is decreased, discs 48 and 49 are caused to separate, bringing said line of intersection closer to the center of the discs, or in other words contracting the supporting surface. When the area of opening 14 increases, spring 55 pushes the discs together expanding the supporting surface.

Our lamp and shade can be embodied in a floor lamp as shown in Fig. 12. Here tubular casting 30 is supported upon telescoping posts 58 and 59, the latter being provided with a base 60. Similarly our lamp can be suspended from the ceiling. The floor lamp of Fig. 12 could be used by attaching base 60 to the ceiling, using posts 58 and 59 of substantially less length.

We claim:—

1. A lamp shade comprising a flexible sheet of material having an opening in its central portion, said sheet having a split extending from said opening to its outer edge, and means rotatably mounted on said sheet on the portion adjacent one of its split edges and engaging the portion adjoining the other of the split edges, said means when rotated causing relative motion of the split edges to and from each other for varying the amount of overlap of the portions adjoining the split edges of the sheet, said means also retaining the split edges in the particular relative position set by its rotation.

2. A lamp shade as claimed in claim 1 in which the rotatably mounted means is a spur gear whose teeth engage the portion adjoining the other of the split edges from that portion which it is mounted upon, said former portion having a part formed for engaging said teeth.

3. A lamp shade having a member for attachment of the shade to a support, said shade formed of a flexible sheet of material having an opening in its central portion, said sheet having a split extending from said opening to its outer edge, the variation in overlap of the sheet at the split controlling the sharpness of the cone shape of the shade, the area of said opening decreasing

as the overlap increases, said member coming within the opening and comprising a portion of greater area than the maximum opening of the shade, and another portion, movable relatively to the first portion, in engagement with the edge 5 of the shade at the opening, said relative motion causing the second portion's place of contact with the edge of the shade at said opening to expand and contract in accordance with the area of said opening, and spring means normally holding said portions in the relative position for maximum expansion of the place of contact.

4. A lamp shade having a member for attachment of the shade to a support, said shade formed of a flexible sheet of material having an opening 15 in its central portion, said sheet having a split extending from said opening to its outer edge, the variation in overlap of the sheet at the split controlling the sharpness of the cone shape of the shade, the area of said opening decreasing 20 as the overlap increases, said member coming within the opening and comprising a portion of greater area than the maximum opening of the shade, and another portion, movable relatively to the first portion, in engagement with the edge 25 of the shade at the opening, said relative motion causing said second portion to extend variably within the first portion and causing thereby the second portion's place of contact with the edge of the shade at said opening to expand and 30 contract in accordance with the area of said opening, and spring means normally holding said portions in the relative position for maximum expansion of the place of contact.

5. A lamp shade having a member for attachment of the shade to a support, said shade formed of a flexible sheet of material having an opening in its central portion, said sheet having a split extending from said opening to its outer edge, the variation in overlap of the sheet at the split controlling the sharpness of the cone shape of the shade, the area of said opening decreasing as the overlap increases, said member coming within the opening and comprising a circular portion of greater area than the maximum opening of the 45 shade, and another portion, movable relatively to the first portion, in engagement with the edge of the shade at the opening, said relative motion causing the second portion's place of contact with the edge of the shade at said opening to expand and 50 contract in accordance with the area of said opening, and spring means normally holding said portions in the relative position for maximum expansion of the place of contact.

6. A lamp shade having a member for attachment of the shade to a support, said shade formed of a flexible sheet of material having an opening in its central portion, said sheet having a split extending from said opening to its outer edge, the variation in overlap of the sheet at the 60 split controlling the sharpness of the cone shape of the shade, the area of said opening decreasing as the overlap increases, said member being formed with an annular groove, a plurality of fingers pivotally mounted in said groove for motion in and out of said groove, and spring means reacting against the member and the fingers for forcing one end of each of the fingers outward of the groove into engagement with the edge of the shade at the opening, said ends moving inwardly or outwardly of the groove in accordance 65 with the area of said opening.

7. A lamp shade having a member with fingers mounted thereon as claimed in claim 6 in which the ends of the fingers engaging the edge of the 70 75

shade are formed with a depression into which the edge of the shade extends.

8. A lamp shade having a member for attachment of the shade to a support, said shade formed of a flexible sheet of material having an opening in its central portion, said sheet having a split extending from said opening to its outer edge, the variation in overlap of the sheet at the split controlling the sharpness of the cone shape of the shade, the area of said opening decreasing as the overlap increases, said member comprising a pair of discs mounted on the support one above the other with freedom of axial motion to and from each other, and spring means normally holding said discs toward each other, one of said discs being in the form substantially of a frustum of a cone having a plurality of radial grooves extending inward from its conical surface, the other of said discs having a plurality of tongues corresponding to said grooves and entering same, said tongues having a surface inclining oppositely to the inclination of the conical surface and intersecting the conical surface, said discs gripping the edge of the shade at the opening along a line passing through the intersections of the inclined surfaces of the tongues and the conical surface, said intersections moving radially inwardly or outwardly in accordance with the area of said opening.

9. A lamp shade as claimed in claim 1 in which the rotatably mounted means is a spur gear whose teeth engage the portion adjoining the other of the split edges from that portion upon which it is mounted, said former portion having a row of spaced holes for engagement with said teeth.

10. A lamp shade comprising a flexible sheet of material having an opening in its central portion, said sheet having a split extending from said opening to its outer edge, a mounting fixedly attached to said sheet on the portion adjoining one of its split edges, and means movably supported by said mounting engaging the portion adjoining the other of the split edges, said means when caused to move on said mounting effecting relative motion of the split edges to and from each other for varying the amount of overlap of the portions adjoining the split edges of the sheet.

11. A lamp shade as claimed in claim 10 in which the movable means in addition to effecting relative motion of the split edges serves as a detent for retaining said edges in the position set at any time by said means.
